UNITED STATES PATENT OFFICE.

EDWARD SWEENEY, OF TRENTON, NEW JERSEY.

TOY.

1,062,129.

Specification of Letters Patent. Patented May 20, 1913.

Application filed November 23, 1912. Serial No. 733,222.

To all whom it may concern:

Be it known that I, EDWARD SWEENEY, a citizen of the United States, residing at Trenton, in the county of Mercer and State of New Jersey, have invented new and useful Improvements in Toys, of which the following is a specification.

The present invention relates to improvements in toys, the primary object of the present invention being the provision of a spring projected device formed to imitate a snake or other animal which when retracted is held against the spring tension within a tube or envelop constituting a handle while a flexible connection provides a means for retaining the same retracted or permitting the same to be projected beyond the tube, there being carried by the opposite end of the flexible connection means for sealing the tube to maintain the retracted object within the tube.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation, the tube being shown partially in section, of the device when not in use. Fig. 2 is a longitudinally sectional view through the complete device with the object retracted and within the tube ready to be released. Fig. 3 is a view showing the device projected with the tube broken away to reduce the length thereof and to show the relative position of the parts.

Referring to the drawings, the numeral 1 designates the tube which constitutes the gripping member to be held in one hand by the operator, while in the sealed end thereof is provided the concentric aperture 2 through which is slidably passed the flexible connection or cord 3. This cord 3, adjacent one end, is provided with a knot 4 which limits the outward movement of the operating button 5, while the extended end 6 with the knot 7, constitutes a means for locking the button 5 in the open end, as at 13, when the device, as will presently appear, is retracted and sealed within the tube 1.

The opposite end of the cord 3 is passed through the head 8 which in the present instance simulates or imitates the head of a snake, the knot 9 being seated within the recessed portion 9' which constitutes the open mouth of the imitation snake.

Having one end fastened fixedly within the tube, at 10, is a flexible covering 11 which when retracted forms a bellows while the opposite end, as at 12, is connected to a contracted portion of the solid head 8 and permits the full extension of the spring 25 which is stationed within the bellows 11 and exerts a normal tension to hold the head 8 in extended position, as clearly shown in Fig. 3.

From the foregoing description, it is evident that with a device constructed according to the present invention, that the operator by holding the tubular member 1 in one hand may pull upon the cord or flexible connection 3 to retain the head 8 in the retracted position, as shown in Figs. 1 and 2, and that by quickly releasing the cord, the spring 25 will project the head and the forward portion of the body to the position as shown in Fig. 3.

When the device is out of use, the head 8 is retracted within the tubular member 1 and the button 5 is inserted within the open end of the tube 1 in the position as shown in Fig. 1, so that the short end 6 of the cord 3 will act as a wedge against the wall as at 13 in Fig. 1, to retain the button firmly within the end of the tube and against the extreme outer end of the head 8. Thus, the object is held within the tube and against the tension of the spring 25. When it is desired to use the toy, the cord 3 is pulled upon to release the button in the open end of the tube 1.

What is claimed is:

1. A toy, including a tubular handle having a sealed end, a bellows mounted therein and having one end fixedly connected to the sealed end, a spring incased within the bellows and having a normal tension to extend without the open end of the tubular member, a solid head member mounted in the outer end of the bellows and disposed to be projected by the spring, a flexible cord connected to said head and slidably mounted in the sealed end of the tubular member and operable exteriorly thereof, and means mounted upon the outer end of the flexible connection for closing the open end of the

tube to retain the solid head and spring contracted within the tubular member.

2. A toy, including a tubular handle having a sealed end, a bellows mounted therein and having one end fixedly connected to the sealed end, a spring incased within the bellows and having a normal tension to extend without the open end of the tubular member, a solid head member mounted in the outer end of the bellows and disposed to be projected by the spring, a flexible cord connected to said head and slidably mounted in the sealed end of the tubular member and operable exteriorly thereof, an operating button mounted upon the flexible connection adjacent the free end and providing a short terminal upon the flexible connection, said button and short terminal coacting to engage the wall at the open end of the tubular member to lock the button therewithin and retain the spring contracted with the head within the tubular member.

3. A toy, having a tubular member provided with a sealed end having a concentric aperture therethrough, a bellows having one end connected within the tubular member, a solid head connected to the opposite end of the bellows, a coiled spring inclosed within

the bellows, said spring within the bellows normally exerting a tension to project a portion thereof and the solid head exteriorly of the tubular member, a cord slidably mounted through the concentric aperture of the tubular member and having one end connected to the head while the other end is projected exteriorly of the tubular member, a button of substantially the same diameter as the open portion of the tube disposed upon the cord adjacent the opposite end to the head and providing a short terminal of greater length than the diameter of the button, and a knot formed upon the extreme end of the short terminal, whereby when the head and spring are contracted within the tubular member, the button and short terminal of the cord coact with the walls of the open end of the tube to seal the same and lock the spring against outward displacement.

In testimony that I claim the foregoing as my own, I have hereto affixed my signature in the presence of two witnesses.

EDWARD SWEENEY.
